RAY W. OREWILER, OF PORTLAND, OREGON.

ALARM-AUGMENTING MEANS.

1,206,725.

Specification of Letters Patent. Patented Nov. 28, 1916.

Application filed October 2, 1914. Serial No. 864,699.

To all whom it may concern:

Be it known that I, RAY W. OREWILER, a citizen of the United States, and a resident of Portland, Multnomah county, State 5 of Oregon, have invented a new and useful Improvement in Alarm-Augmenting Means, of which the following is a specification.

This invention relates generally to calling, or alarm mechanism, and particularly 10 to the alarm mechanism of telephones, and has for its object the providing of means whereby the alarm is augmented so as to be more readily heard.

In manufacturing establishments the 15 ringing of the bells of a telephone is frequently not loud enough, or is not continued long enough, to be heard over the din of the shop; and by my invention I combine with this primary alarm mechanism, auxiliary alarm mechanism thrown into and out 20 of action by the telephone alarm mechanism, by so doing giving a loud alarm. And I furthermore make my auxiliary alarm mechanism adjustable so that the alarm may 25 be continued for as long a period as desired, and thus render the same more effective.

The construction and operation of my invention are more readily understood by a 30 description of the accompanying drawings.

In the latter, Figure 1, is an elevation showing one type of my invention as used in connection with a telephone circuit. In this 35 construction of my invention, an electrical horn is thrown into a battery circuit, by the operation of a relay placed in the telephone circuit, and the horn is maintained in said battery circuit for a predetermined period of time after such operation by a 40 pneumatic cylinder and piston therein; Fig. 2, is a sectional detail of the lower end of the cylinder and the piston reciprocable therein; Fig. 3 is a fragmental plan view showing a detail of construction; and Fig. 4 is a fragmental plan view showing an 45 alternate detail of construction.

In these drawings, a wall bracket, 1, has 50 mounted upon it an electro-magnet, 2. Said magnet is provided with an axial bore, 3, in which a movable core or armature, 4, is reciprocable. Into the lower end of this core, 3, is threaded the rod, 5, of a piston, 5^a, which reciprocates in the cylinder 6. A check valve represented by, 7, fixed in the lower end of this cylinder, 6, permits air to 55 flow into the latter, but checks the out-flow.

The cylinder, 6, is fastened on the wall bracket, 1, by a strap, 6^a.

In the lower end of the cylinder, 6, is a needle valve element, 8, (see Fig. 2,) consisting of the air-duct, 8^a, and the adjustable screw, 8^b.

On the piston rod, 5, is a cross arm, 9, one end of which is slotted and such end slides on the guide-rod, 10, so as to hold the piston rod against rotation. On the other end of 65 the cross-arm, 9, is fixed a vertical arm, 11, the upper end of which is curved as at, 12. A push button switch, 13, is so mounted on the bracket, 1, that the push-button, 14, will lie in the path of motion of the arm, 11. In 70 this way when the piston-rod, 5, is raised the arm, 11, will bear against and push in the button, 14, thereby closing the switch. 13. 16 and 17 represent the circuit wires of the telephone branch.

18, represents a commercial relay switch, which is mounted on the bracket, 1, and is connected with the telephone circuit wires, 16 and 17. In my invention this relay switch is so connected with the circuit wires, 80 19 and 20, of the electro-magnet, 2, that when the relay is operated by the closing of the telephone circuit, the circuit of the battery, 21, will be closed; and since the electro-magnet, 2, is also in the circuit of the 85 battery, 21, such closing will energize the electro-magnet 2.

24, is an electric horn mounted on the bracket, 25, fastened on the shelf, 26. The wires 22, 23, and 27 form a circuit through 90 the battery 21, said circuit being controlled, by a push-button switch 13.

The operation of this type of my device is as follows: Whenever the telephone circuit is closed the electro-magnet, 2, will be 95 energized through the closing of the relay switch, 18, and the magnet core, 4, will thereupon be pulled up to the position shown on the broken lines in Fig. 1. This movement will cause the arm, 11, to bear 100 against and push in the push-button, 14, thereby closing the battery circuit of the horn, 24, and causing the latter to blow steadily. If desired, the arm may be crimped as shown by 11' in Fig. 4 so as to 105 cause the horn to give a succession of short blasts. The upward movement of the armature, 4, will pull up the piston in the cylinder, 6, and by the adjustment of the valve, 8, in the lower end of the pneumatic cylind- 110

der, the return movement of the piston, after the circuit of the magnet, 2, has been broken by the interruption of the telephone circuit, may be controlled as desired, with 5 reference to the length of time the sounding of the horn, 24, shall continue; for the push-button switch, 13, will be maintained in a closed state until the arm 11, is dropped away from it. However the alarm may be 10 discontinued at any time, by manually forcing the piston down.

I claim:

1. In an electric signaling apparatus, the combination with a main circuit, of an auxiliary circuit, energizing means therefor, a signaling device in said auxiliary circuit, a switch, normally open, for closing said auxiliary circuit, a shunt circuit connected with the auxiliary circuit, an electro-magnet in 20 said shunt circuit provided with a movable core, a relay switch connection between the shunt circuit and the main circuit, a member carried by the movable core adapted to bear against and close the switch of the 25 auxiliary circuit when the magnet is energized, and adjustable means for retarding

the return of the core to normal position after the magnet has been deenergized.

2. In an electric signaling apparatus, the combination with a main circuit, of an auxiliary battery circuit, an electric horn in 30 said auxiliary circuit, a push-button switch, normally open, for closing said auxiliary circuit, a shunt circuit connected with the auxiliary circuit, an electro-magnet in 35 said shunt circuit provided with a movable core, a relay switch connection between the shunt circuit and the main circuit, a fluid cylinder located beneath the magnet, a piston carried by the magnet core operating in said 40 cylinder, an arm carried by the piston rod adapted to bear against and close the push-button switch of the auxiliary circuit when the core is attracted by the magnet, and a needle valve in said cylinder for retarding 45 the return of the core to normal position after the magnet has been deenergized.

RAY W. OREWILER.
